ELECTROMAGNETIC DEVICE

Irvin W. Cox, West Allis, Wis., assignor to Cutler-Hammer, Inc., Milwaukee, Wis., a corporation of Delaware

Filed Apr. 14, 1958, Ser. No. 728,285

11 Claims. (Cl. 317—185)

This invention relates to electromagnetic devices and more particularly to electromagnetic operators of the fluid-damped type.

While not limited thereto, the invention is especially applicable to alternating current electromagnetic devices for operating contacts and the like.

To decrease undesirable variations in magnetic attraction due to the cyclic variations of the alternating current and thereby to decrease the noise, it has been the usual practice to provide alternating current electromagnetic devices with a phase shifting shading coil. Such shading coil is not only a wattage consuming device, particularly at higher frequencies, but also overheats the pole faces, increases the rate of wear and necessitates the use of more conductor material such as copper to conduct the increased holding current. High speed magnets have the inherent disadvantage that the repeated high-shock armature impacts against the pole faces of the laminated core cause "mushrooming" and wear, misalignment and noise. This is transmitted, sometimes resonantly, to the contacts to significantly affect the electrical life thereof.

It has been proposed to damp an alternating current electromagnetic device by means of a dashpot or to partially immerse the same in oil. However, it has been found that these devices do not provide critical damping, that is, damping sufficient to arrest resonance, nor do they render the electromagnetic device quiet in operation.

Accordingly, a general object of the invention is to provide an improved electromagnetic device which overcomes the aforementioned disadvantages to a significant degree.

A more specific object of the invention is to provide an improved electromagnetic device of the fluid-damped type which affords critical damping thereof.

Another specific object of the invention is to provide an improved alternating current electromagnetic operator wherein a plurality of magnetic forces are applied to the armature symmetrically around a central axis and fluid damping is symmetrically applied to the armature over a large area.

A further specific object of the invention is to provide an improved alternating current electromagnetic operator which is exceptionally quiet in operation and has a markedly longer mechanical life.

Another object of the invention is to provide an alternating current electromagnetic device having reduced weight and power consumption compared to its work capacity and which can be readily and economically constructed.

Further objects and advantages of the invention will hereinafter appear.

While the apparatus hereinafter described is effectively adapted to fulfill the objects stated, it is to be understood that I do not intend to confine my invention to the particular preferred embodiment of electromagnetic device disclosed, inasmuch as it is susceptible of various modifications without departing from the scope of the appended claims.

The invention will now be described with reference to the accompanying drawings, wherein

FIGURE 1 is a top view of the electromagnetic device constructed in accordance with the invention;

FIG. 2 is a sectional view taken along lines 2—2 of FIG. 1;

2

FIG. 3 is a partly sectional view taken along lines 3—3 of FIG. 1; and

FIG. 4 is a sectional view taken along lines 4—4 of FIG. 3.

5 Referring to FIGS. 2 and 3 of the drawings, there is shown an electromagnetic device having a generally cup-shaped housing member 10 provided with an internal, substantially semi-spherical depression 12 centrally of its bottom portion and an internal annular groove 14 around the rim of its open end. A generally cup-shaped supporting member 16 having an exteriorly stepped, circular depending outer wall 17 is partially telescoped into housing member 10 to close the open end of the latter. In this position the rim of housing member 10 abuts against shoulder 18 of the supporting member and the two members are sealed to one another by a resilient O-ring 19 accommodated in annular groove 14. Supporting member 16 is additionally provided with a central bore 20 and a tubular inner wall 22 surrounding the bore and depending into the interior of the housing member. Supporting member 16 is further provided with two pairs of angularly spaced, reamed apertures 24, also shown in FIG. 1, around the periphery of the upper flat portion thereof for providing terminal connections as hereinafter described. Supporting member 16 may have symmetrically interposed between holes 24 angularly spaced and internally threaded holes 26, shown in FIG. 1, extending part way into supporting member 16 for securing a contact structure or the like to the upper portion of the device.

20 A cylindrical electromagnet having a laminated core 28 with an axial bore 30 and provided with a plurality of angularly spaced, depending pole pieces 32, more clearly seen in FIG. 4, and a coil 34 surrounding each pole piece is rigidly embedded in suitable plastic or thermosetting material 36 such as epoxy in the annular space between outer wall 17 and inner wall 22 of supporting member 16. Inserts 38, each having a tapped hole 40 extending part way therein from the outside, are accommodated in apertures 24 and surrounded by plastic material 36 for securing the same to and insulating the same from supporting member 16. Inserts 38 are provided with a frusto-conical flange flaring outwardly at their outer ends and substantially complimentary to the reamed portions of apertures 24 to prevent insertion thereof completely through the latter. The inner ends of inserts 38 are provided with a peripherally knurled flange 42 to rigidly secure the same from rotation in the plastic material and an annular groove 44 to facilitate connection of coils 34 thereto. The ends of the coil wires may be wrapped around grooves 44 and soldered therein to form an electrical connection. Suitable external electrical terminals may be threaded into tapped holes 40.

25 A cylindrical, laminated armature 46 having an axial bore 48 corresponding to and coaxial with bore 30 of core 28 is mounted for reciprocatory movement in the space between the electromagnet and the bottom portion of housing member 10 within the housing member. 30 Armature 46 is embedded in a frame 50 of plastic or thermosetting material such as epoxy with its annular sealing surface 52 exposed to the free end faces of pole pieces 32.

35 A generally inverted cup-shaped member 54 is provided with a pair of peripherally knurled flanges 56 and embedded thereby coaxially in plastic frame member 50. Member 54 is provided with a central aperture 58 having a form complimentary to a partial sphere. An actuator rod 60 having a spherical end portion 62 is secured to member 54 by insertion of the rod through aperture 58 to the extent that spherical end portion 62 engages the complimentary portion of aperture 58. A disc-shaped re-

taining member 64 having a substantially semi-spherical depression 66 centrally thereof for accommodating the remainder of spherical end portion 62 is inserted in cup-shaped member 54 and the rim of the latter is forged inwardly to secure the parts together. The restricted portion of aperture 58 may be a predetermined amount larger in diameter than rod 60 adjacent such restricted portion to afford a limited amount of movement of spherical end portion 62 in its supporting structure.

A generally inverted cup-shaped member 68 is provided with an axial aperture through its closed end for accommodating rod 60. An armature return spring 70 surrounds rod 60 within cup-shaped member 68 and is compressed between members 54 and 68 to return the armature to its normal position when the electromagnet is deenergized. Member 68 is provided adjacent its upper closed end with an annular groove 72 for receiving an internal circular bead 74 on the large end of a generally conical, flexible diaphragm 76. The small end of diaphragm 76 is reentrant inwardly of the diaphragm and is provided with an axial aperture surrounded by an integral bead 78 locked in a complimentary, annular groove 80 intermediate the ends of rod 60. Member 68 is accommodated within the tubular inner wall 22 of supporting member 16 and is provided at its rim with an annular flange 81 for abutment against the free end of such tubular inner wall. The large end of conical diaphragm 76 is compressed between member 68 and inner wall 22 to retain bead 74 in groove 72.

A bearing plate 82 having a central aperture 84 for accommodating rod 60 is secured by screws 86 or the like to the upper surface of supporting member 16 to close bore 20 from the atmosphere. The external end of rod 60 may be threaded for securing movable contacts or the like thereto.

The space within housing member 10 surrounding the armature is completely filled with a predetermined quantity of damping fluid 87 such as oil or the like for controlling operation of the device. To control the effect of the damping fluid, armature frame 50 is provided with a plurality of apertures 88 of predetermined sizes angularly spaced in the portion of armature frame 50 between armature 46 and member 54. Damping fluid may also be provided within diaphragm 76 to fill the space surrounding rod 60 inasmuch as the diaphragm operates with a constant volume, or some damping fluid 87 may enter this space along rod 60 through the aperture in member 68.

Core 28 of the electromagnetic device is constructed by winding a ribbon-like strip of magnetic material onto an arbor to produce a cylindrical core having a plurality of spirally wound thin laminations and a bore axially therethrough. Portions of the strip are preferably cut out by an automatic notching machine as the strip is being wound to form pole pieces therebetween. The portions cut out may be of the same size but progressively spaced as the strip is wound. The coils may be preformed and then inserted on the pole pieces. Inserts 38 are placed in apertures 24 and electrically connected to the coil wires. This subassembly is then placed within the generally annular space in supporting member 16 and thermo-setting potting material forced in the spaces therebetween to rigidly secure the magnet to the supporting member. The potting material also surrounds inserts 38 to rigidly secure the same to the supporting member.

Armature 46 and member 54 are molded in a frame 50 of thermo-setting material to form a rigid structure. Rod 60 may then be inserted in aperture 58 and retaining disc 64 secured in place as hereinbefore described. Spring 70, member 68 and diaphragm 76 may then be assembled on rod 60 in the order named. Alternatively, rod 60, disc 64, spring 70, member 68 and diaphragm 76 may be assembled on member 54 prior to molding of the latter and the armature in frame 50. The completed sub-assembly may then be forced into bore 20 to the extent that flange 81 abuts the free end of tubular inner wall 22. Bearing

plate 82 is secured to supporting member 16 to substantially seal the interior of the device.

Suitable damping fluid 87 is then placed in housing member 10, O-ring 19 placed in groove 14 and supporting member 16 telescoped within housing member 19 into abutting engagement with shoulder 18 to complete the device.

While the armature is shown in FIGS. 2 and 3 in its closed or sealed position, spring 70 normally maintains the gaps between armature 46 and the pole faces open. Under this condition, damping fluid 87 surrounds the armature and its frame 50. When the coils are energized, the magnetic forces in the gaps attract the armature upwardly. The damping fluid flows from the gaps through apertures 88 and around armature frame 50, spring 70 is compressed and the armature seals into engagement with the pole faces. As a result, rod 60 moves upwardly to actuate contacts or the like mounted on the upper portion of supporting member 16. The cyclic variations of the alternating current which induce a corresponding variable magnetic flux in the gaps would normally tend to vibrate the armature and impact the same against the pole faces as it approaches a sealed condition. The damping fluid absorbs such vibration to reduce noise and wear. As will be apparent from FIGS. 2 and 3, diaphragm 76 is provided with a configuration including a reentrant portion so that it operates with constant volume when the armature is actuated and, thus, may be completely filled with damping fluid. When the coils are deenergized, spring 70 returns the armature to its normally open position. As the armature starts to disengage the pole faces, the film of damping fluid on the sealing surfaces of these parts damps any vibration tending to be caused by the alternating magnetic flux, thus to prevent impact of the armature against the pole faces.

The damping fluid is maintained within the device by atmospheric pressure as well as by the enclosure. The loading to which the armature is subjected as by return spring 70 is less than that which would cause it to cavitate and draw atmospheric air therein. This is for the reason that air might emulsify the damping fluid that is, form compressible air bubbles in the damping fluid to deteriorate its damping characteristics. The actual loading is preferably set well below the cavitation loading to afford a safety factor.

An essential feature of the invention is the provision of a structure wherein the magnetic forces are symmetrically distributed around the central actuator rod 60 and large areas for contact with the damping fluid are provided by casting both the magnet and the armature in thermosetting material. Also, apertures 88 affording flow of damping fluid through armature frame 50 are selected to provide optimum operating conditions affording, along with the large surfaces critical damping as hereinbefore described. The improved device affords the objects and advantageous results hereinbefore described through a wide range of operating frequencies. Thus, the low power consumption, the increased pole face life, low noise, and the increased life of all the moving parts are attainable whether the coil energizing frequency under which it is operated is the commercial frequency of 60 cycles or a higher frequency in the range of 400 cycles and up.

I claim:

1. In an alternating current electromagnetic device, in combination, a housing having a cavity therein and being open at one end, a laminated electromagnet in one end of said cavity to close said open end and having a pole face, means surrounding said pole face to provide a relatively large surface area in the plane thereof, armature means having a relatively large surface area opposed to the surface area of said pole face, means mounting said armature means for reciprocatory movement in the other end of said cavity, actuator means connected to said armature means and extending to the exterior of said

housing, and damping fluid completely filling and being confined in said other end of said cavity around said armature means.

2. The invention defined in claim 1, wherein said armature means comprises a laminated magnet armature member, a frame of thermosetting material having said armature member embedded therein with one surface of said armature member exposed for engagement with said pole face, said frame providing a relatively large surface area in the plane of said one surface, and at least one aperture in said frame affording a flow passage for said damping fluid.

3. The invention defined in claim 1, together with a bearing plate secured to said housing and having a restricted aperture for accommodating said actuator means to substantially close the interior of said housing from the atmosphere, resilient means normally biasing said armature means away from said pole face, energization of said electromagnet overcoming the force of said resilient means to attract said armature to said pole face, and said force of said resilient means being a predetermined amount less than the force which would cause said armature means to draw atmospheric air into said cavity when said electromagnet is deenergized.

4. The invention defined in claim 1, together with substantially conical resilient means connected between said actuator means and said housing for sealing said other end of said cavity from the atmosphere and to maintain the volume around said armature substantially constant when the latter is operated.

5. In a high frequency alternating current electromagnetic device, in combination, a separable housing having a cavity therein, an electromagnet having a pole face, thermosetting material embedding said electromagnet in one portion of said cavity with said pole face exposed, said thermosetting material providing a relatively large surface area in the plane of said pole face, an armature having a sealing surface opposed to said pole face and normally biased away from the latter and mounted for reciprocatory movement in another portion of said cavity, a frame of thermosetting material having said armature embedded therein with said sealing surface exposed and providing a relatively large surface area opposed to the first mentioned surface area, and damping fluid filling the space around said armature and said frame within said another portion of said cavity.

6. The invention defined in claim 5, wherein said housing comprises two substantially cup-shaped portions, the open end of one portion being telescoped within the open end of the other portion and having a shoulder for abutting against the rim of said other portion, said other portion having a groove adjacent its rim, and resilient means within said groove for sealing said portions to one another.

7. In an alternating current electromagnetic device, in combination, a generally cylindrical housing having a first portion and a second portion connected to one another, said first portion having an axial bore surrounded by an inner tubular wall forming a substantially annular cavity therearound opening into said second portion, a cylindrical electromagnet having a plurality of angularly-spaced pole pieces and an operating coil surrounding each pole piece, said electromagnet being embedded in said annular cavity in thermosetting material with the pole faces exposed, said thermosetting material providing along with said pole faces a relatively large surface area in the plane of said pole faces, a cylindrical armature embedded in a frame of setting material with a surface of the arma-

ture exposed for sealing with said pole faces when said electromagnet is energized, said frame of thermosetting material providing along with said armature a relatively large surface area in the plane of said sealing surface, an actuating member connected to said armature frame and extending through said bore exteriorly of said housing, and damping fluid filling the space surrounding said armature and said frame within said second portion of said housing.

10. The invention defined in claim 7, together with a generally cup-shaped member within said inner tubular wall having an annular flange at its rim for abutting against the free end of said inner tubular wall and an aperture in its closed end for accommodating said actuating member and an annular groove around its closed end, a substantially conical resilient diaphragm in said bore having a bead at its large end retained in said annular groove by said tubular inner wall, and the small end of said diaphragm having a reentrant portion provided with an aperture surrounding and connected to said actuating member, said diaphragm sealing said cavity from the atmosphere.

9. The invention defined in claim 8, wherein said reentrant portion is of a length to afford operation of said diaphragm at a substantially constant interior volume throughout the operating stroke of said actuating member.

10. The invention defined in claim 9, together with a bearing plate having an aperture for guiding said actuating member secured to said first housing portion for closing said bore therein, and a ball and socket joint affording restricted pivotal movement of said armature on said actuating member.

11. In an alternating current electromagnetic device, in combination, an alternating current electromagnet comprising a magnetic member and at least one energizing coil for energizing said magnetic member, said magnetic member having a pole face forming one side of a gap, a magnetic armature member having a face forming the other side of said gap and being mounted for reciprocatory movement to close and open said gap, a housing for said electromagnet and said armature, means associated with said electromagnet providing with said pole face an enlarged damping surface area larger than the magnetically effective area of said pole face at said gap, means associated with said armature and movable therewith providing with said armature face an enlarged damping surface area larger than the magnetically effective face area of said armature at said gap, said enlarged surface areas being opposed to one another, and damping liquid within said housing maintaining said armature and said pole face and said means providing said enlarged damping surface areas completely immersed at all times, and said damping liquid cooperating with said enlarged surface areas to prevent armature vibration tending to be caused by the alternating magnetic flux thereby eliminating the use of shading coils and the like.
